FURNACE STRUCTURE

John W. Throckmorton and John S. Wallis, New York, N.Y., assignors, by mesne assignments, to Yuba Consolidated Industries, Inc., San Francisco, Calif., a corporation of Delaware

Application February 27, 1957, Serial No. 642,800

4 Claims. (Cl. 126—109)

This invention is concerned with heaters in general. More specifically, the invention pertains to tall, cylindrical, upright furnaces of the pressure fired type having a single cylindrical bank of vertical heat exchange tubes spaced near the inner wall of the combustion chamber and forming a circle of large diameter.

It has been found that with this type of furnace, there are set up, within any upright portion of the furnace, down drafts of the products of combustion. These down drafts are caused by a temperature gradient that is set up as the heat is transferred from the products of combustion to the heat exchange tubes by radiation. Such down drafts have a tendency to unduly cool the flame of the burner or other source of heat. Thus, the flame becomes partially quenched by reason of the introduction of currents of relatively cool gases that are directed against the flame by reason of the recirculation indicated. One method that has been employed heretofore to overcome this difficulty is that of "top firing" a vertical furnace, and drawing off the flue gases at the bottom. This does avoid the quenching effect of the recirculation gases, but this method is not as efficient as it might be since the combustion products are only allowed to make one pass by the heat exchange tubes. Therefore much of the potential heat is not transferred. In addition, the top firing method creates the necessity for providing duct work that extends the full height of the furnace in order to be able to make use of a preheat exchange for preheating the intake air to the burners. Such lengthy duct work, to say nothing of the more complicated structure for mounting a burner at the top of the furnace, creates a relatively expensive addition to the necessary structure.

Consequently, it is an object of this invention to provide an improved heater that overcomes the above indicated disadvantages and difficulties.

Furthermore, it is an object of this invention to provide a heater that has a furnace chamber that is fired at one end thereof and has its flue gases discharged near the same end.

Another object of this invention is to provide a vertical furnace having one or more pressure type burners at the bottom thereof that forces the flame and hot combustion products centrally to the full height of the furnace chamber, and that has the flue gases withdrawn from the chamber near the periphery at the bottom.

Still another object of the invention is to provide a vertical type furnace which employs a single bank of vertical heat exchange tubes therein. The furnace being centrally fired at the bottom of the furnace with the burner directed axially within the furnace chamber. The furnace also includes a conical baffle at the top of the closed chamber, and has flue gas exit openings located at the bottom of the furnace chamber and spaced radially from the burner or burners.

Still another object of the invention is to provide a vertical type furnace having a single bank of vertical heat exchange tubes near the furnace wall and an upshot

2

burner located in the center of the bottom area of the furnace, with flue gas exit openings located near the periphery of the bottom outside of the burner. The furnace also has an air intake duct that is adjacent to a flue gas removal duct for convenient connection of the two ducts to the proper passages of a heat exchanger, in order to provide convenient and easy heat transfer for lowering the temperature of the stack gases and preheating of the intake air.

10 Briefly, this invention includes a vertical type furnace which comprises, among other elements, a closed top combustion chamber. In addition the furnace comprises means for receiving heat from the combustion of fuel in said chamber, and at least one burner located near the bottom of said chamber and directed upward. The furnace also comprises means for forcing the products of combustion from said burners with sufficient velocity to cause them to circulate substantially the full height of the chamber, and comprises flue gas exit means located near the bottom of said chamber spaced from said burner.

Certain embodiments of the invention are described below, by way of illustration thereof, and illustrated in the drawings in which:

25 Fig. 1 is an elevation showing the furnace largely in longitudinal cross section;

Fig. 2 is an enlarged transverse cross section of the furnace taken on the line 2—2 of Fig. 1 looking in the direction of the arrows;

30 Fig. 3 is an elevation of another embodiment of the invention, showing the furnace largely in longitudinal cross section;

Fig. 4 is an enlarged cross section view of the Fig. 3 embodiment taken along the line 4—4 of Fig. 3 looking in the direction of the arrows; and

35 Fig. 5 is a fragmentary elevation with the furnace largely in longitudinal cross section, showing an additional embodiment of the invention employing the same features as that shown in Fig. 3, but including a preheat element in addition to a blower for additionally inducing the flow of flue gases out of the furnace.

40 Referring to Figs. 1 and 2, it will be observed that there is a stack 11 to which the furnace is connected for disposing of the flue gases. The furnace has a vertical, closed-top construction which includes a cylindrical outer shell 12 made of steel or other structural material. This shell 12 is supported by a plurality of upright I beams 13 which form the framework for the furnace. There is at least one cross support beam 14 resting on opposite framework I beams 13. This acts as a top support for various of the internal elements of the furnace which may be clamped or bolted to the under edge thereof. I beams 13 extend down and act as legs 15 to hold the furnace above the floor level.

45 The furnace shell 12 may be attached to the I beams 13 in any convenient manner (not shown) such as by clamping or bolting. Integrally attached to the lining within shell 12 there is a closed top structure 18 that surrounds a centrally located inverted cone baffle 19. Baffle 19 is preferably supported from the cross beam 14 by means of a vertical cylindrical extension 20. Baffle 19 has a solid surface construction, so that there is no exit at the top of the furnace for any of the flue gases.

50 Around the periphery of the top member 18 there is support for the upper ends of a cylindrical bank of vertical heat exchange tubes 21. This support structure is not shown in detail as it is of a conventional nature. The furnace chamber is formed within a cylindrical side wall of heat resistant material 22. This wall 22 is formed on the inside of shell 12 in the usual manner for providing a fire resistant, heat reflecting liner on the inside of the furnace chamber.

At the bottom of the furnace chamber there is a floor structure 25 which is supported within a peripheral tube-supporting annular structure 26 that is attached to the outer shell 12 of the furnace in any convenient manner (not shown). Centrally located in the floor 25 there is a group of four burners 27 that are directed axially upward within the furnace chamber.

The construction of these burners is conventional and the details thereof are not shown. It may be noted that they are constructed to be in the nature of high velocity, or jet burners, such that the flame and hot products of combustion are forcibly ejected upward in the unobstructed central portion of the furnace to the full height of the furnace chamber.

Underneath the floor member 25 of the furnace there is attached a closed housing 28 which surrounds and encloses the side of the burners 27 beneath floor 25. Leading from one corner of housing 28 there is an intake air duct 29. Duct 29 is directly connected to the output of a forced draft blower 30. There is included in this connection via duct 29, a preheat heat-exchange unit 31. By this arrangement the intake air for burners 27 is supplied under pressure in order to create the necessary high velocity action required. There is a fuel supply pipe 34 connected to each burner 27, at the bottom thereof. These pipes are connected to a source of supply for the fuel, in any convenient manner (not shown).

There is an annular flue gas exit opening 35 at the periphery of the furnace chamber near the floor level. This opening is formed by an annular flange 37 of a ring or baffle of heat resistant material 36. The baffle 36 stands vertically upward from the floor 25 and the horizontal flange 37, as viewed in cross section extends radially outward from the vertical baffle 36 toward the tubes 21 near the base thereof, but leaves an adequate annular open space around the tubes 21 for passage of the flue gases. Baffle 36 together with its flange 37 thus forms an annular manifold 38 at the lower peripheral corners of the combustion chamber. Connected to this manifold 38 there is a flue gas exit conduit 39 that carries the flue gases leaving the furnace chamber, through the heat exchange element 31 and on into the stack 11 for disposal. The baffle 36 extends only a short distance upwardly and covers small portions at the bottom of the heat exchange tubes 21.

It will be observed from Fig. 2 that there are employed four burners 27. However, it will be clear to any one skilled in the art that a single burner of adequate size might be employed instead of the four smaller burners shown.

The embodiment illustrated in Figs. 3 and 4 is quite similar to that of Figs. 1 and 2. The major difference in this embodiment of the invention, over that of Figs. 1 and 2, lies in the use of different heat exchange tubes 47. Tubes 47 include both a long upper smooth portion 47a and a short lower portion having extended surfaces 47b thereon. The elements of the furnace which are unchanged over corresponding elements in Figs. 1 and 2 are given the same reference numerals, so that no further explanation thereof need be given here.

In the Figs. 3 and 4 embodiment a baffle 48 which is constructed of heat resistant material, extends vertically upward from the floor 25. This baffle 48 extends to a height substantially level with the lowest part of the smooth portion 47a of the heat exchange tubes. Thus, the extended surface section 47b of the tubes 47, fills up a considerable amount of the radial space which lies between the baffle 48 and the heat resistant side wall 22 of the furnace chamber.

The extended surface sections 47b of the tubes 47 stop somewhat above the tube supporting annular structure 26, so that in effect a manifold space 49 is formed in a similar location as was manifold 38 of the Figs. 1 and 2 embodiment.

By employing the structure of the furnace illustrated in Figs. 3 and 4, the heat transfer to the circular bank of tubes 47 is carried out in the form of a radiant heat exchange from the flame and hot gases forced upwardly from the burners plus convection heat effects from the downwardly flowing cooler gases over the smooth upper portion 47a of the tubes. Then at the lower portion 47b of the tubes 47, i.e., within the annular flue gas exit space radially between wall 48 and the furnace chamber side walls 22, there is a heat exchange by convection only. Such heat exchange is aided by the use of fins or extended surfaces 47b.

As clearly indicated in the drawings, the heat exchange tubes are exposed throughout a large percentage of their entire length to direct radiation from the central column of flame and hot combustion gases, and the relatively short cylindrical baffles 36 and 48 form outlet manifolds in all of the drawings. 48 additionally forms a short convection section in Figs. 3, 4 and 5.

The flue gases are carried off (as was the gas in the earlier modification) via the flue gas exit duct 39. It will be noted that in this embodiment there is not shown any heat exchange unit for preheat exchange purposes. In some instances the omission of a preheat exchange unit may be permissible.

In Figure 5, an additional embodiment of the invention is illustrated. It will be noted that the furnace structure is the same as that used in the Figures 3 and 4 embodiment. Consequently, the same reference numerals apply to the similar elements and no additional explanation thereof is necessary.

In the Figure 5 embodiment there is shown an additional element in the form of a forced draft blower 51. Blower 51 is shown mounted on top of intake air blower 30, for the sake of convenience. It will be observed that the blower 51 is connected to exhaust duct, or conduit, 39 and acts to aid in the withdrawal of flue gases from the furnace via the conduit 39. By making use of the additional blower 51 as well as the forced draft intake air blower 30, the firing conditions of the furnace while operating, may be more closely controlled than would be the case with only the pressurizing forced draft blower 30 on the air intake side. Thus, the degree of negative pressure on the exhaust end of the furnace may be separately regulated or controlled. At the same time the degree of intake pressure applied is controlled by blower 30.

It is to be noted that although there are only three different embodiments of the invention illustrated, it will be clear to one skilled in the art that various other arrangements might readily suggest themselves. Furthermore, the individual elements of these embodiments may be combined in other and different ways without falling outside the scope of this invention. For example the furnace illustrated in Figs. 1 and 2 might additionally include a blower on the exhaust duct, or it might not employ any preheat heat exchanger. Similarly, the furnace illustrated in Figs. 3 and 4 might include a preheat heat exchanger but not employ any exhaust draft blower, e.g. 51.

Operation

Referring first to Figure 1 in particular, the operation of a furnace according to this invention will be described with some emphasis on the benefits that are to be had. The furnace is heated by the four jet type upshot burners 27 which provide flames that are directed axially upward close to the axis of the furnace chamber. Intake air for the burners is supplied under pressure by the blower 30 and delivered through the conduit 29 via the heat exchange preheat element 31. Then after the mixing and ignition of intake air with the fuel, the products of combustion are ejected upward in flow paths generally indicated by dashed arrows shown. It will be observed that the flame and hot combustion gases in their upward flow

do not contact the heat exchange tubes. Since the top of the furnace chamber is completely enclosed the hot gases cannot escape, but are all returned down along the side walls of the furnace chamber in the vicinity of the tubes 21. Some of this reverse flow or recirculation would take place even though the flue gases were to be removed at the top of the furnace. However, in a furnace according to this invention these hot gases and products of combustion, which are recirculated as the heat is withdrawn (in the manner indicated), are now withdrawn at the bottom of the furnace chamber out through the annular exhaust opening 35 which surrounds the base of tubes 21. These flue gases are then drawn out through the conduit 39 and via the intake heat exchange unit 31 to the stack 11 for disposal of the spent gases.

It is pointed out that the conical baffle 19 is not absolutely necessary. However, it has a double function in use. First the turning back of the products of combustion is aided with a minimizing of eddy currents etc. to disturb a smooth flow. Second the baffle 19 becomes heated by the products of combustion which strike against it so that it acts as a secondary source and reradiates heat to the smooth portion of the primary heat exchange tubes, e.g., tubes 21 or 47.

It is to be particularly noted that by reason of the withdrawal of flue gases at the bottom of the furnace, they are prevented from being turned back into the stream of gases being ejected from the burners. For this reason there is no harmful quenching action applied to the flames of the burners. Furthermore, it is to be noted that the flue gas exit duct 39 is radially located close to the intake air duct 29, so that there is necessary only a minimum of duct work involved for employing a preheat exchange between the flue gases and the intake air.

It will be observed that the same general flow action of the products of combustion takes place in the embodiment according to Figures 3 and 4. The only difference is the fact that withdrawal of the flue gases begins somewhat higher from the floor of the furnace and for a distance vertically including the length of the extended surface elements 47b. Also there is an additional primary heat exchange carried out between the heat exchange tubes 47 and the products of combustion, by means of convection action only.

It will be noted that the flue gas exit opening 35 might take different forms without departing from the spirit of the invention. For example, there might be individual openings surrounding each of the heat tubes 21.

While various embodiments of the invention have been described in considerable detail in accordance with the applicable statutes, this is not to be taken as in any way limiting the invention, but merely as being descriptive thereof.

It is claimed:

1. A vertical furnace comprising a tall hollow un-

obstructed cylindrical shell, a single cylindrical bank of vertical heat exchange tubes spaced from one another and located close to but spaced from the inner surface of the cylindrical shell and exposed to the axis of said shell throughout the major portion of their height, a bottom plate closing the lower end of said shell, one or more upshot burners mounted near the center of the bottom plate, means for closing the furnace shell at the top, means operatively associated with said burners for forcing the flame and hot combustion gases upwardly from the burners through the central unobstructed space in the shell of the furnace out of contact with said cylindrical tube bank, means forming a short cylindrical exhaust manifold surrounding the lower ends of the tubes near the bottom of the furnace shell at its periphery, said manifold being coaxial with said shell and open at its top, and means for creating a draft withdrawing the relatively cool combustion gases from said cylindrical manifold at the bottom of the furnace, the parts being so arranged that the cylindrical bank of heat exchange tubes is directly exposed to radiant heat only from the flame and hot combustion gases moving upwardly near the axis of the furnace shell and that said tubes are subjected to convection heat from the relatively cool combustion gases flowing downwardly near the cylindrical furnace wall into said manifold.

2. A vertical furnace, in accordance with claim 1, further comprising extended surface means on the surfaces of the tubes within the manifold where the tubes are subjected only to convection heat from the down flowing combustion gases.

3. A vertical furnace, in accordance with claim 1, further comprising an inverted conical baffle suspended from and projecting centrally downward from the furnace top adapted to absorb heat from the hot gases and to reradiate heat to the tubes near their upper ends and adapted to assist the hot flue gases to be returned downwardly behind and around the tubes.

4. A vertical furnace, in accordance with claim 1, further comprising extended surface means on the surfaces of the tubes within the manifold where the tubes are subjected only to convection heat from the down flowing combustion gases and an inverted conical baffle suspended from and projecting centrally downward from the furnace top adapted to absorb heat from the hot gases and to reradiate heat to the tubes near their upper ends and adapted to assist the hot flue gases to be returned downwardly behind and around the tubes.
